UNITED STATES PATENT OFFICE.

EDWARD E. JOHNSON, OF ST. PAUL, MINNESOTA.

PROCESS OF DIE FORGING.

Original application filed February 13, 1920, Serial No. 358,449. Divided and this application filed February 27, 1922. Serial No. 539,433.

To all whom it may concern:

Be it known that I, EDWARD E. JOHNSON, a citizen of the United States, residing at St. Paul, in the county of Ramsey and State 5 of Minnesota, have invented certain new and useful Improvements in Processes of Die Forging, of which the following is a specification.

My invention relates to processes of die- 10 forging. It relates particularly to processes of shaping couplings suitable for interior screw-threading at both ends by die-forging cylindrical blanks after they have been heated to a temperature suitable for 15 performing such operation. This application is a division of my prior application Serial Number 358,449 filed February 13, 1920.

The full objects and advantages of my 20 invention will be apparent from the foregoing description, and the novel features embodied in my inventive idea will be particularly pointed out in the claims.

Referring to the accompanying drawings 25 which illustrate steps in the performance of my process, Fig. 1 is a view in perspective of a section of cylindrical metal tube constituting a blank from which a coupling is made. Figs. 2 to 8 are detail views showing the different positions of the forging dies and coupling blank during the forging operation. Fig. 9 is a side elevational view 30 of the coupling after it has been finished in the dies. Fig. 10 is a view in perspective of one of the die members which I employ.

In carrying out my invention, tubular sections such as the section 12 shown in Fig. 1 are cut from a metal tubing of the proper size. The blanks thus produced are heated to the proper temperature for forging and are placed one at a time between a plural- 40 ity of radially operating dies 14 which are reciprocated in unison in any suitable manner such as by the mechanism disclosed in my prior application above referred to. Each die face as shown in Fig. 10 consists of a middle portion 16 and two end portions 18 which are raised above the middle portion and are inclined slightly in upward directions as they extend away from the middle portion. These end portions are beveled at each side as indicated at 20 and at their outer ends are provided with curved 45 depressions 22. The manner in which the

blank is forged will be understood by referring to Figs. 2 to 8. Fig. 2 is an end view in which the blank 12 and the dies 14 are shown in the position which they occupy at the inception of the forging 60 operation. The end portions of the dies are in contact with the surface of the blank, in the position here shown while as indicated by dotted lines the middle portions of the dies have not yet reached the blank. 65 Figs. 3 and 4 are sectional views transversely through the middle portion of the blank and the dies, Fig. 3 showing the dies advanced so that they just contact with the blank, and Fig. 4 showing the blank and 70 dies in final position. In the latter figure, the hexagonal shape of the middle portion of the coupling having faces 24 is shown. The shape is referred to as hexagonal since the number of dies which I employ is pref- 75 erably six. Figs. 5 and 6 are sectional views transversely through the dies and the blank midway of an end portion of the latter. Fig. 5 shows the dies advanced sufficiently 80 to partly shape the blank, while Fig. 6 shows the dies advanced into final position whereby the end portions of the coupling have a reduced hexagonal exterior surface, the faces of which are separated by longitudinal 85 radially extending ribs 26 which are produced on account of the die faces being beveled as shown at 20 in Fig. 10. Figs. 7 and 8 are end views, Fig. 7 showing the dies advanced sufficiently to partly shape 90 the blank while Fig. 8 shows the dies ad- 95 vanced into final position. The end of the coupling in Fig. 8 is shown with the curved portions 28 which are formed by the de- 100 pressions 22 at the ends of the die faces. It will be apparent from Figs. 2 to 8 that the coupling is produced with reduced end portions or necks having cylindrical ends merging into an outer surface of hexagonal form, the faces of which are separated by reinforcing ribs which extend longitudi- 105 nally from the middle portion to the ex- treme ends of the coupling. Fig. 9 shows the exterior appearance of the coupling after it has been shaped in the dies. By referring to Fig. 10 which shows one of the several cooperating dies, it will be ap- 110 parent how the final shape is given to the coupling by means of the die faces. The middle portion 16 of each die face forms one of the faces 30 of the middle portion

of the coupling, the end portions 18 form the faces 32 of the end portions of the coupling, the beveled portions 20 provide for the ribs 26 and finally, the curved depressions 22 form the curved elevations or protuberances 28.

The advantages of my process will be understood from the foregoing description. Bulging or distortion of the inner wall of 10 the blank is avoided and the cylindrical interior shape of the contracted end portions is maintained so that these portions may be readily provided with interior screw threads. By employing my process in 15 which heated cylindrical tubular blanks are subjected to radially-directed inward pressure applied at regular intervals around the blank to give a polygonal shape thereto, I am able to dispense with a mandrel and still 20 maintain the interior cylindrical surface of the blank. Since the pressure is equally distributed around the blank, there is no distortion of the internal surface from an approximately cylindrical shape. The result 25 of the applied pressure is to cause an exterior flow of metal to produce the polygonal exterior shape but the interior curve of the blank acts in the manner of an arched structure and the interior cylindrical shape 30 is maintained. In the manufacture of the coupling, the making of the end portions of polygonal shape permits the retention of the inner cylindrical surface without any interior supporting mandrel when the end 35 portions are reduced by radial inward pressure in the dies. It is of importance that the inner surface be kept substantially cylindrical in order to provide a suitable surface for screw-threading. If an attempt is 40 made to reduce the end portions without the use of an interior mandrel and between dies which are concaved instead of flat, the interior surface will be bulged into a shape which is approximately polygonal, and 45 hence, not suitable for screw-threading. The provision of the ribs 26 strengthens the coupling, and these ribs serve to take up the surplus material when the end portions are

contracted between the dies. The protuberances 28 not only strengthen the coupling 50 at its ends but take care of surplus material when the ends of the blank are contracted to a smaller dimension between the dies. This surplus material would be a disadvantage if it were squeezed out longitudinally 55 of the blank but is turned into an advantage by squeezing it out into protuberances at the outer ends of the faces of the end portions.

I claim:

1. The process of die-forging which consists in heating cylindrical tubular blanks and subjecting the end portions of said blanks to radially-directed inward pressure applied at regular intervals around the blank to contract said end portions and give 60 a polygonal exterior shape thereto.

2. The process of die-forging which consists in heating cylindrical tubular blanks, subjecting the end portions of said blanks to radially-directed inward pressure applied at regular intervals around the blank to contract said end portions and give a polygonal exterior shape thereto, and subjecting the middle portion of said blanks to radially-directed inward pressure applied 70 at regular intervals around the blank to give a polygonal exterior shape to said middle portion.

3. The process of forming couplings which consists in cutting sections from cylindrical 80 tubing to form blanks, heating said blanks, subjecting the end portions of said blanks to radially-directed inward pressure applied at regular intervals around the blank to contract said end portions and give a polygonal 85 exterior shape thereto, subjecting the middle portion of said blanks to radially-directed inward pressure applied at regular intervals around the blank to give a polygonal exterior shape to said middle portion, 90 and providing said contracted end portions with internal screw threads.

In testimony whereof I hereunto affix my signature.

EDWARD E. JOHNSON.
